UNITED STATES PATENT OFFICE.

JOHN D. ARNOLD, OF PITTSBURGH, PENNSYLVANIA.

DESIGN FOR A MINIATURE CHURCH FOR HOME DEVOTION.

44,912.

Specification for Design.

Patented Nov. 25, 1913.

Application filed July 31, 1913. Serial No. 782,357. Term of patent 7 years.

To all whom it may concern:

Be it known that I, JOHN D. ARNOLD, a citizen of the United States, residing at Pittsburgh, in the county of Allegheny and State of Pennsylvania, have invented a new, original, and ornamental Design for Miniature Churches for Home Devotion, of which the following is a specification, reference being had to the accompanying drawing, forming part thereof.

I claim:

The ornamental design for a miniature church for home devotion, as shown.

JOHN D. ARNOLD.

Witnesses:

H. HECK,
C. M. CLARKE.
